UNITED STATES PATENT OFFICE.

JOHN J. DAVIS, OF PITTSBURG, PENNSYLVANIA.

DESIGN FOR A BADGE.

No. 38,487.

Specification for Design.

Patented March 26, 1907.

Application filed February 27, 1907. Serial No. 359,698. Term of patent 14 years.

To all whom it may concern:

Be it known that I, JOHN J. DAVIS, a citizen of the United States, and a resident of Pittsburg, in the county of Allegheny and State of Pennsylvania, have invented a new, original, and ornamental Design for Badges, of which the following is a specification, reference being had to the accompanying drawing, forming part thereof.

The figure is a plan view of a badge, showing my new design.

I claim—

The ornamental design for a badge, as shown.

JOHN J. DAVIS.

Witnesses:

D. C. JENNINGS,
J. N. COOKE.
